ROCK DRILL

Elmer G. Gartin, Claremont, N. H., assignor to
 Sullivan Machinery Company, a corporation of
 Massachusetts

Application May 29, 1933, Serial No. 673,490

18 Claims. (Cl. 255—53)

This invention relates to rock drills, and more particularly, but not exclusively, to improvements in an adjustable support for a hammer rock drill of the portable, hand held type.

5 An object of this invention is to provide an improved adjustable support. Another object is to provide an improved adjustable support for a rock drill of the portable, hand held type. A further object is to provide an improved adjustable 10 drill support having embodied therein improved counterbalancing means for a drill thereon and improved drill guiding means whereby an operator may handle the drill in an improved manner and with facility. These and other objects will, 15 however, hereinafter more fully appear.

In the accompanying drawings, there are shown for purposes of illustration one preferred form and several modifications thereof which the invention may assume in practice.

20 In these drawings,—

Fig. 1 is a side elevational view of the preferred illustrative embodiment of the improved adjustable support, a rock drill being shown in position thereon and parts shown in section to show details of construction.

Fig. 2 is a detail view taken substantially on line 2—2 of Fig. 1.

Fig. 3 is a detail sectional view taken substantially on line 3—3 of Fig. 2.

30 Fig. 4 is a transverse sectional view taken substantially on line 4—4 of Fig. 3.

Fig. 5 is a view similar to Fig. 1 showing a modified form of construction.

Fig. 6 is a similar view showing a further modification.

Fig. 7 is a detail view of the support shown in Fig. 6.

Fig. 8 is a detail elevational view showing a still further modified form of construction.

40 Fig. 9 is a side elevational view with parts shown in section of the support shown in Fig. 8.

Fig. 10 is a detail sectional view taken on line 10—10 of Fig. 8.

Fig. 11 is a view similar to Fig. 1 showing still another modified form of construction.

Fig. 12 is a side elevational view with parts shown in longitudinal section illustrating a modified form of drill counterbalancing means.

Fig. 13 is a transverse sectional view taken substantially on line 13—13 of Fig. 12.

Fig. 14 shows a still further modified form of construction.

In the illustrative embodiment of the invention shown in Figs. 1 to 4, inclusive, there is shown an adjustable drill support generally design-

nated 1 having mounted thereon a rock drill, generally designated 2, of the usual hand held hammer type. The rock drill, which is of a standard design, comprises a casing 3 containing a hammer motor of the usual reciprocating piston type and supporting within its front chuck housing 4, a drill steel 5. Attached to the rear head of the drill casing is a usual grasping handle 6. The rock drill 2 is of the portable hand held type normally adapted to drill down holes while supported by the operator; and the improved adjustable support 1 is provided whereby the drill may be used to drill horizontal or upwardly inclined holes without the necessity of burdening the operator with the entire weight of the drill. 15

The preferred form of the improved adjustable drill support 1 comprises a standard or column 7 herein of tubular form having telescopically arranged within its lower end an adjustable foot member 8 providing an abutment engaging point 20

9 adapted to engage the mine or quarry floor. The lower end of the column is split at 10 to provide a clamp having an operating handle 11 whereby the adjustable foot member 8 may be held in its different positions of adjustment. The 25 upper end of the column 7 has threaded therein a support member 12 having a lateral abutment engaging point 13 adapted to engage the mine or quarry wall in the manner shown in Fig. 1.

Slidably mounted on the column 7 is a support 30 member 14 in the form of a sleeve having suitable clamping means 15 whereby the same may be clamped in its different positions of adjustment to the column. This slidable support 14 is provided with a trunnion engaging or swivel 35 member 16, as shown in Fig. 2, adapted to fit within a socket 17 formed in a swiveled guide member 18. Secured to this swiveled guide member is a drill steel guide and support 19 herein providing a hook-shaped guiding portion 20 for 40 embracing the drill steel 5 and within which the drill steel is adapted to rest during the drilling operation. In this illustrative construction, the improved drill counterbalancing means comprises a cylindrical counterbalancing weight 21 slidably 45 guided within the bore 22 of the column 7 and having connected thereto at its upper end a flexible element 23, herein a cable or rope. This cable is secured to the weight and passes upwardly from the weight through the interior of 50 the column and outwardly through an opening 24 formed in the support 12. Journaled on a pin 25 carried by the support 12 is a sheave or pulley 26, and the rope 23 passes upwardly around this pulley and then downwardly along the side of the 55

column and around a sheave or pulley 27 journaled on a pin 28 carried by a bracket 29 integral with the sliding sleeve 14. The rope 23 passes around the sheave 27 and then laterally for connection at 30 to a lug or projection 31 secured to the drill casing. The swivel member 18 is provided with a lateral opening 32 of suitable dimensions so that the same may be lifted upwardly and removed laterally from the swivel or trunnion 16.

The mode of use of the improved adjustable drill support will be clearly apparent from the description given. The drill support is placed in position between the mine or quarry floor and the mine or quarry wall in the manner shown in Fig. 1 with the abutment engaging point 9 engaging the floor and the lateral abutment engaging point 13 engaging the wall. The drill steel 5 of the rock drill is then placed in position within the hook-shaped guiding portion 20 of the drill guide 19 and the counterbalancing rope 23 attached to the projection 31 on the drill casing, the operator grasping the handle 6 of the drill to partially support the weight thereof and to direct the same during the drilling operation. The counterbalancing weight 21, through the cable and pulley connection, tends to counterbalance the weight of the drill and to aid in the feeding of the drill toward the work. If it is desired to drill holes either upwardly or downwardly at different inclinations, as indicated at A and B in Fig. 1, the operator merely swings the drill about the trunnion support 16 either upwardly or downwardly, as desired. If it is desired to drill holes at a higher elevation, as indicated at C in Fig. 1, the clamp 15 of the sliding support 14 is released and the support 14 moved upwardly along the column to a position indicated, the clamp thereafter being tightened 40 to hold the support in position on the column. The column may be adjusted vertically to vary the locus of engagement of the point 13 with the mine or quarry wall simply by releasing the clamp 10 and moving the column upwardly along the foot piece 8 to the desired position, the clamp 10 thereafter being tightened to hold the parts in adjusted position. As the drill steel penetrates the rock the weight 21, which at all times maintains the counterbalancing rope 23 taut, slides 45 downwardly within the column bore.

In the modification shown in Fig. 5, the column 35 and the sliding support 36 are substantially identical to those described in a preferred form of the invention. However, in this form of the invention the sliding support 36 has no clamp 15 and is at all times free to slide upwardly and downwardly along the column. In this instance, the foot piece 37 is secured rigidly within the lower end of the column, while the upper abutment engaging support 38 is secured to an adjustable member 39 of tubular form telescopically arranged within the upper end of the column bore. The upper end of the column is provided with a clamp 40 having an adjusting handle 41 so that the adjustable member 39 may be clamped in its different adjusted positions within the column. Slidably mounted within the member 39 is a counterbalancing weight 42 similar to the weight 20 above described and having a rope or cable 43 passing around pulleys 44 and 45 carried by the abutment engaging support 38 and sliding support 36, respectively. The swivel drill guide 46 is preferably identical to the guide 18.

In the use of this form of the invention, the operator may change the position of the drill

support 36 relative to the column simply by sliding the support upwardly or downwardly along the column. The abutment engaging support 38 may be adjusted to engage the mine wall at different locations simply by releasing the clamp 40 and sliding the tubular member 39 either upwardly or downwardly into the desired position, the clamp 40 thereafter being tightened to lock the parts. Otherwise the operation of this form of the invention is the same as that above 10 described.

In the modified form of construction shown in Figs. 6 and 7, the column, sliding drill support and upper abutment engaging support are substantially identical to those described in the 15 preferred form of the invention. In this modified construction, however, an adjustable foot piece 47 is telescopically arranged within the lower end of the column and is provided with an abutment engaging point 48. This element 47 is 20 of tubular form and is traversed by a series of openings 49 along its length within which a locking pin 50 carried by the column is insertible to hold the foot piece in the desired adjusted position. In this form of the invention a counterbalancing weight 51 is arranged within the column, and is provided with a rope or cable 52 guided by pulleys 53 and 54 carried by the upper abutment engaging support and the sliding drill support, respectively, as in the preferred form of the invention. In this construction, the weight is provided with a conical or tapered lower end 55 so as the same moves downwardly within the column, the point thereof guides the weight within the bore 56 of the tubular foot piece 47, the weight 35 moving within the tubular body of the foot piece as the drill is fed inwardly. The upper abutment engaging supporting is herein provided with lateral portions 57 each having an abutment engaging point 58, the points being arranged in 40 laterally spaced relation for engagement with the mine or quarry wall at spaced points, thereby preventing undesirable rocking of the column about its axis as might occur in the form where- 45 in but a single point is provided.

In the modification shown in Figs. 8, 9 and 10, the adjustable element 39 for the upper abutment engaging support 38, as shown in Fig. 5, is provided with adjusting means whereby the same may be slid inwardly and outwardly within the 50 upper end of the column in an improved manner. In this improved construction, the adjustable element 39 has secured along the length thereof a rack 59 with which engages a pinion 60 journaled within lateral lugs 61 formed on the upper 55 end of the column 35 and having an operating lever 61. When the pinion 60 is rotated by this lever, the rack 59 is moved either upwardly or downwardly to adjust the member 39 in either direction, as desired.

In the modified form of construction shown in Fig. 11, the column, lower foot piece, and the upper abutment engaging support are substantially identical to those described in the preferred form of the invention. In this construction, how- 65 ever, the counterbalancing weight is made in tubular form as at 62 and is slidable upwardly and downwardly on the exterior of the column. Fastened at 63 to this weight is a rope or cable 64 guided by a pulley 65 carried by the upper abut- 70 ment engaging support and a pulley 66 carried by a sliding drill support 67 slidably mounted on the exterior of the tubular weight 62. The swiv- 75 eled drill guide 68 is identical to those above described. In this form of the invention, as the

5 drill is fed inwardly, the weight 62 moves downwardly along the column and within the sliding support 61, the weight 62 being of sufficient length so as to permit the drill steel to be fed inwardly to the desired distance without the weight sliding out through the support 61.

10 In the modified form of construction shown in Figs. 12 and 13 the counterbalancing weight 69 is mounted within the column and has connected to its opposite ends a rope or cable 70. This cable passes around a pulley 71 carried by the upper abutment engaging support and by a pulley 72 journaled on a shaft 73 carried by the column. The side of the column is provided with an opening 15 74 to permit the pulley to extend thereinto, as shown in Fig. 12. Secured by an attaching device 75 to the rope 70 is a rope or cable 76 guided by a pulley 77 carried by a bracket 78 secured to the sliding drill support 79, the cable 20 76 extending laterally and secured at its end to the rock drill. The swiveled drill guide 80 is identical to those described in the other forms of the invention. In this construction, when the drill is fed inwardly the weight 69 moves downwardly 25 within the column and the cable 76, due to its attachment 75 to the cable 7, effects counterbalancing of the drill. The sliding drill support 79 is provided with a clamp 81 for securing the same in its different positions of adjustment along the 30 column.

35 In the modification shown in Fig. 14, the column and counterbalancing weight structure is identical to that described in the form of the invention shown in Fig. 11. In this construction, however, secured to the upper and lower ends of the column is a support 85 having a portion 86 extending parallel with the column and inwardly bent ends 87, 87. Slidably mounted on the support 85 is a sliding drill support 88 having a swivel 40 drill guide 89 similar to those above described. Attached at 90 to the upper end of the tubular weight 91 is a rope or cable 92 guided by a pulley 93 carried by the upper abutment engaging support 94 secured to the upper end of the column. The cable 92 extends around the pulley 93 and 45 downwardly along the side of the column and is guided by a pulley 95 journaled on the sliding drill support 88, the cable 92 extending around the pulley 95 and laterally for attachment to the rock drill. The sliding drill support 88 is provided with a clamp 96 for securing the same in its adjusted position along the member 85.

50 As the mode of use of the various drill supports shown in the modifications shown in Figs. 6 to 14, inclusive, are substantially identical to those described in the forms of the invention shown in Figs. 1 to 5, inclusive, and as the various methods of use of the improved drill supports described herein will be clearly obvious to those skilled in the art, further description thereof is deemed unnecessary.

55 As a result of this invention it will be noted that an improved adjustable drill support is provided whereby a rock drill of the portable, hand held type may be utilized to drill horizontal and upwardly inclined holes in an improved manner. It will further be noted that an improved adjustable drill support is provided which may be readily set up in working position and which may be 60 readily moved from place to place. It will still further be noted that an improved adjustable drill support is provided having embodied therein improved counterbalancing means for the drill whereby the operator may handle the drill in a more efficient and facile manner, particularly

65 during the drilling of horizontal or upwardly inclined holes. These and other uses and advantages of the invention will be clearly apparent to those skilled in the art.

70 While there are in this application specifically described one form and several modifications thereof which the invention may assume in practice, it will be understood that these are shown for purposes of illustration, and that the invention may be further modified and embodied in various other forms without departing from its spirit or the scope of the appended claims.

75 What I claim as new and desire to secure by Letters Patent is:

1. An adjustable support for rock drills comprising an upstanding column having abutment engaging supports at its opposite ends, one support extending at right angles with respect to the other for engagement with the floor and wall respectively of the working face, a drill guide 15 mounted on said column for adjustment longitudinally therealong and on which a rock drill is adapted to be guided for bodily movement relative to the guide, and drill counterbalancing means associated with the column and guide and 20 connected to the rock drill for counterbalancing the weight of the rock drill irrespective of its bodily guided position with respect to said guide and column.

2. An adjustable support for rock drills comprising an upstanding column having abutment engaging supports at its opposite ends, a drill guide mounted on said column for adjustment longitudinally therealong and on which a rock 30 drill is adapted to be guided for bodily movement 35 relative to the guide, and drill counterbalancing means associated with said column and drill guide and connected to the rock drill for counterbalancing the weight of the rock drill irrespective of its bodily guided position with respect to said guide 40 and column, said counterbalancing means including a counterbalancing weight guided by said column longitudinally of the latter and connections between said weight and the rock drill.

3. An adjustable support for rock drills comprising an upstanding supporting member having abutment engaging elements at its opposite ends, one abutment element extending laterally and the other longitudinally with respect to said supporting member for engagement with the floor 50 and wall respectively of the working face, a drill guide mounted on said supporting member for adjustment longitudinally therealong and on which a rock drill is adapted to be guided for bodily movement relative to the guide, and drill 55 counterbalancing means for counterbalancing the weight of the rock drill irrespective of its bodily guided position with respect to said guide and column, said counterbalancing means including a counterbalancing weight and a cooperating 60 flexible element having its intermediate portion between the weight and rock drill engaging said drill guide.

4. An adjustable support for rock drills comprising a tubular standard having abutment engaging points at its opposite ends, drill guiding means on said standard and on which a rock drill is adapted to be guided for bodily movement with respect thereto, and drill counterbalancing means for counterbalancing the weight of the 70 rock drill irrespective of its bodily guided position with respect to said guiding means and standard, said counterbalancing means including a counterbalancing weight slidably guided within said tubular standard, and means for connecting said 75

weight to the rock drill guided by said guiding means.

5. An adjustable support for rock drills comprising a tubular standard, a drill guide mounted on said standard and on which a rock drill is adapted to be guided for bodily movement relative to the guide, and drill counterbalancing means for counterbalancing the weight of the rock drill irrespective of its bodily guided position with respect to said guide and standard, said counterbalancing means including a counterbalancing weight guided by said standard longitudinally with respect to the latter, a pulley at the upper end of said standard, a pulley on said drill guide, and a cable connected to said weight and rock drill and having its intermediate portion guided by said pulleys.

6. An adjustable support for rock drills comprising a standard having abutment engaging points at its opposite ends, a drill guide mounted on said standard for adjustment longitudinally therewith and on which a rock drill is adapted to be guided for bodily movement relative to the guide, and drill counterbalancing means for counterbalancing the weight of the rock drill irrespective of its bodily guided position with respect to said guide and standard, said counterbalancing means including a counterbalancing weight guided by said standard longitudinally of the latter, and a connection between said weight and the rock drill guided by said guide.

7. An adjustable drill support for rock drills comprising a column having a bottom abutment engaging support, an adjustable upper abutment engaging support therefor, a drill guide on said column, and drill counterbalancing means comprising a counterbalancing weight guided by said column, pulleys carried by said adjustable abutment engaging support and said drill guide, respectively, and a cable attached to said weight and guided by said pulleys and adapted for attachment to a rock drill guided by said guide.

8. An adjustable drill support for rock drills comprising a column having a bottom abutment engaging support, an adjustable upper abutment engaging support therefor, a drill guide adjustable upwardly and downwardly along said column, and drill counterbalancing means comprising a counterbalancing weight guided by said column, pulleys carried by said adjustable abutment engaging support and said drill guide, respectively, and a cable attached to said weight and guided by said pulleys and adapted for attachment to a rock drill guided by said guide.

9. An adjustable support for rock drills comprising a standard having extensible means for varying the length thereof, a drill guide mounted on said standard for adjustment longitudinally with respect thereto and on which a rock drill is adapted to be guided for bodily movement relative to the guide, and drill counterbalancing means for counterbalancing the weight of the rock drill irrespective of its bodily guided position with respect to said guide and standard, said counterbalancing means including a counterbalancing weight, a pulley on the upper end of said standard, a pulley on said adjustable guide, and a cable attached to said weight and rock drill and having its intermediate portion guided by said pulleys.

10. In a rock drill support, a tubular column having at its upper and lower ends abutment engaging points, a sleeve guided on said column for movement longitudinally thereof, means for securing said sleeve in different positions longitudinally of said column, a drill guide element carried by said sleeve and on which a rock drill is adapted to be guided for bodily movement relative thereto, and means for counterbalancing the weight of the rock drill guided by said guide element irrespective of its bodily guided position with respect to said guide element and column including a pulley journaled on the upper end of said column, a pulley journaled on said sleeve, a drill counterbalancing weight guided within said tubular column, and a cable guided by said pulleys and secured to the counterbalancing weight and connectible to a rock drill guided by said drill guide element.

11. In a rock drill support, a tubular column comprising telescopically arranged tubular elements, one element being extensible relative to the other to vary the length of the column, each element having an abutment engaging point and means for securing said extensible tubular element in adjusted position, a sleeve guided on said column for movement longitudinally thereof, means for securing said sleeve in different positions longitudinally of said column, a drill guide element carried by said sleeve and on which a rock drill is adapted to be guided for bodily movement relative thereto, and means for counterbalancing the weight of the rock drill guided by said guide element irrespective of its bodily guided position with respect to said guide element and column including a pulley journaled on the upper end of said column, a pulley journaled on said sleeve, a drill counterbalancing weight guided within said tubular column, and a cable guided by said pulleys and secured to the counterbalancing weight and connectible to a rock drill guided by said drill guide element.

12. In a rock drill support, a tubular column, an abutment member secured to the upper end of the column and having an abutment engaging point, a foot piece telescopically arranged within the lower end of the column and having an abutment engaging point, means for securing the foot piece in its different adjusted positions with respect to the column, a sleeve slidably guided on said column for adjustment lengthwise thereof, means for securing said sleeve in different adjusted positions longitudinally of the column, a drill guide element carried by said sleeve and on which a rock drill is adapted to be guided for bodily movement relative thereto, and means for counterbalancing the weight of the rock drill guided by said guide element irrespective of its bodily guided position with respect to said guide element and column including a pulley journaled on said abutment member at the upper end of the column, a pulley journaled on said sleeve, a counterbalancing weight slidably guided within said column, and a cable guided by said pulleys and secured to said counterbalancing weight, said abutment member at the upper end of the column having an opening through which said cable extends into connection with said weight, said cable also secured to a rock drill guided by said drill guide element.

13. In a rock drill support, a tubular column having at its lower end an abutment engaging point, an extensible tubular member telescopically engaging the upper portion of the column, means for securing said extensible member in its different adjusted positions with respect to the column, a member secured to the upper end of said extensible member and having an abutment engaging point, a sleeve guided on said column, a drill guide element carried by said sleeve, a

14. In a rock drill support, a tubular column having at its upper and lower ends abutment engaging points, a sleeve guided on said column for movement longitudinally thereof, means for securing said sleeve in different positions longitudinally of said column, a drill guide element carried by said sleeve and on which a rock drill is adapted to be guided for bodily movement relative thereto, and means for counterbalancing the weight of the rock drill guided by said guide element irrespective of its bodily guided position with respect to said guide element and column including a pulley journaled on the upper end of said column, a pulley journaled on said sleeve, a drill counterbalancing weight guided within said tubular column, and a cable guided by said pulleys and secured to the counterbalancing weight and connectible to a rock drill guided by said drill guide element.

5 pulley journaled on said abutment member at the upper end of said extensible member, a pulley journaled on said sleeve, a counterbalancing weight guided within said extensible member and column, and a cable guided by said pulleys and secured to said counterbalancing weight and connected to a rock drill guided by said drill guide element, said abutment member at the upper end of said extensible member having an opening 10 through which said cable extends into connection with said weight.

14. In a rock drill support, a column having abutment engaging points at its opposite ends, a counterbalancing weight in the form of a sleeve 15 guided on said column for movement longitudinally thereof, a sleeve guided on said counterbalancing weight for movement longitudinally thereof, a drill guide element carried by said last mentioned sleeve, a pulley journaled on the upper 20 end of said column, a pulley journaled on said last mentioned sleeve, and a cable guided by said pulleys and secured to said counterbalancing weight and connectable to a rock drill guided by said drill guide element.

25 15. An adjustable support for rock drills comprising a column having an abutment engaging point at its lower end and a laterally projecting abutment engaging point at its upper end for engagement respectively with the floor and wall 30 of the working face, a drill guide mounted on said column for adjustment along the length of the latter and relative to which a rock drill is adapted to be guided for bodily movement relative thereto, means for securing said guide to said 35 column in its different adjusted positions, and drill counterbalancing means associated with said column and drill guide for counterbalancing the weight of a rock drill guided by said guide, said counterbalancing means connected to the 40 rock drill and operative to counterbalance the weight of the drill irrespective of the bodily guided position of the latter relative to said guide and column.

45 16. An adjustable support for rock drills comprising a column having an abutment engaging point at its lower end and a laterally projecting abutment engaging point at its upper end for engagement respectively with the floor and wall of the working face, a drill guide mounted 50 on said column for adjustment along the length of the latter and relative to which a rock drill is adapted to be guided for bodily movement relative thereto, means for securing said guide to said column in its different adjusted positions, and drill counterbalancing means associated with said column and drill guide for counterbalancing the weight of a rock drill guided by said guide

irrespective of the bodily guided position of the rock drill with respect to the latter and said column and including a counterbalancing weight guided by said column, a pulley at the upper end of said column, a pulley on said drill guide, and a cable secured to said weight and drill and having its intermediate portion guided by said pulleys. 5

17. An adjustable support for rock drills comprising an upstanding column having an abutment engaging point at its lower end and a laterally projecting abutment engaging point at its upper end for engagement respectively with the floor and wall of the working face, a drill guide mounted on said column for adjustment longitudinally therealong, and means for securing said guide in its different adjusted positions with respect to said column, said guide embodying a swivelled guide element relative to which a rock drill is adapted to be guided, said guiding element being swivelly mounted to enable the rock drill to be guided in different angular positions with respect to said column, and drill counterbalancing means whereby the weight of the drill is counterbalanced irrespective of the bodily guided and angular positions thereof relative to said guide, said counterbalancing means associated with said column and guide and connected to the rock drill. 10 15 20 25

18. An adjustable support for rock drills comprising an upstanding column having an abutment engaging point at its lower end and a laterally projecting abutment engaging point at its upper end for engagement respectively with the floor and wall of the working face, a drill guide 30 mounted on said column for adjustment longitudinally therealong, and means for securing said guide in its different adjusted positions with respect to said column, said guide embodying a swivelled guide element relative to which a rock 35 drill is adapted to be guided, said guiding element being swivelly mounted to enable the rock drill to be guided in different angular positions with respect to said column, and drill counterbalancing means whereby the weight of the drill 40 is counterbalanced irrespective of the bodily guided and angular positions thereof relative to said guide, said counterbalancing means associated with said column and guide and connected to the rock drill and including a counterbalancing 45 weight guided by said column longitudinally with respect to the latter, a pulley at the upper end of said column, a pulley on said drill guide, and a cable secured to said weight and drill and having its intermediate portion guided by said pulleys. 50 55

ELMER G. GARTIN.
